(71) Applicant: **Mitsubishi Rayon Co., Ltd.**, Chiyoda-ku (JP)

* cited by examiner

(72) Inventors: **Hiroyuki Okazaki**, Toyohashi (JP); **Yoshie Tanizaki**, Toyohashi (JP)

Primary Examiner — Robin V Webster

(73) Assignee: **Mitsubishi Rayon Co., Ltd.**, Chiyoda-ku (JP)

(74) Attorney, Agent, or Firm — Oblon, McClelland, Maier & Neustadt, L.L.P.

(**) Term: **15 Years**

(21) Appl. No.: **29/537,003**

(57) **CLAIM**

(22) Filed: **Aug. 21, 2015**

The ornamental design for a degassing/aeration membrane module, as shown and described.

(30) **Foreign Application Priority Data**

Feb. 24, 2015 (JP) 2015-003797

(51) **LOC (10) Cl.** **23-01**

DESCRIPTION

(52) **U.S. Cl.**

USPC **D23/209**

(58) **Field of Classification Search**

USPC ... D23/207, 209; 96/4, 6; 95/46; 210/497.01
CPC B01D 19/0031

See application file for complete search history.

(56) **References Cited**

FIG. 1 is a front, top, and left side perspective view of a degassing/aeration membrane module;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.
